AUTOMATIC TELECOMMUNICATION SYSTEM

Jean R. A. Escande, Lyon, France, assignor to International Standard Electric Corporation, New York, N. Y., a corporation of Delaware

Application March 10, 1943, Serial No. 478,695
In France October 31, 1941

19 Claims. (Cl. 179—16)

1 This invention relates to new and useful improvements in electrical signaling and communication systems, and particularly in circuit arrangements for automatic telephone systems.

One of the objects of the invention is to simplify and reduce the cost of equipment necessary for setting a selector under the control of a register which is operated by directive or reverte impulses.

Another object of the invention is to eliminate in automatic telephone switching systems the marking multiples and associated hunting or marking switches which are usually provided between the selectors and their control circuits, and thus to insure simplicity and correct functioning by eliminating the sources of circuit breaks, faulty connections and other troubles.

In accordance with the present invention, during the selection of a desired group the selector sends reverte impulses towards a control switch which forms part of a temporarily connected control circuit. The reverte impulses are used for determining a desired group of trunks terminating in the selector bank in accordance with the positioning of a register under the control of the called number dialed by the calling subscriber. If all the trunks in the desired group are busy then the switch will continue to hunt until a trunk becomes idle. The control switch insures hunting by the selector in the selected group only during one rotation.

According to a feature of the invention, the control switch consists of a group of relays operating as counting relays, and the circuits are so arranged that whenever the selector leaves the terminals of a group of trunks, an impulse is sent over the control circuit and the closure of the test circuit of the group of trunks is prevented until the number of impulses received from the selector corresponds to those received from the register.

According to another feature of the invention, while the selector continues to hunt during the busy condition of all the trunks in the desired group, the register relays will continue to receive impulses from the selector and insure the continuance of the hunt.

An object of the invention is the provision of a switching system in which reverte or directive impulses may be sent over the register control circuit. According to one feature of the invention, selective impulses may be received on a rotating element, such as a commutator, and the impulses controlling the setting of the selector are

2 sent in series and received until a pair of counting relays is reached which have been marked by said element.

These and other features of the invention will be more fully explained in the following detailed description with the aid of the drawings in which:

3 Fig. 1 is a schematic representation of an automatic system the circuits of which embody the various features of the invention;

4 Fig. 2 shows the connection between the register and the control circuit;

5 Fig. 3 diagrammatically represents an embodiment of the invention in a group selector;

6 Figs. 3a and 3b show the control circuit for the selector and should be placed below one another and below Fig. 3;

7 Fig. 3c shows a modification of Fig. 3a; and

8 Figs. 4, 4a and 4b, placed one below the other, illustrate the final selector and its control circuit embodying the present invention.

9 Fig. 1 shows a connection including a primary finder CP, a secondary finder CS, a register E linked to the connection by means of a finder CE, a primary selector SP, controlled by a group of relays in the register, a group selector SG controlled by a group control circuit G connected with the group selector over finder CG, and a final selector SF controlled by a final control circuit F connected with the final selector by means of finder CF.

10 Fig. 3 shows the circuit of the group selector SG and Figs. 3a and 3b the control circuit therefor.

11 The purpose of the group of counting relays in Fig. 3b is to register the impulses received from the register E and to receive the impulses sent back by selector SG during its rotation. The control circuit is arranged, as best shown in Fig. 3c, to stop the group selector by testing the c wires in the level marked by the selection. The operation of the circuits of Figs. 3-3c is as follows:

12 A preceding selector in the chain tests an idle group selector over make-busy jack JO, a back contact of relay T and a resistance. A potential is then placed on wire b in the manner shown in

13 Fig. 2. In the register E a battery is connected over a resistance to the impulse sending contacts I. This battery is connected over wire b, back contacts of T and CO (Fig. 3), a resistance, to the starting relay CS (Fig. 3a) of the control circuit.

14 Relay CS operates relays LS and AS which actuate the finders CG of all available control circuits.

15 When the circuit of the selector in use is found by brush g of a finder CG, the relay Gt operates as well as the relay Sh, ground, front AS, jack OJ, sequence switch, cam P, winding of Gt, brush

g and the battery connected to the back contact of CO.

Relay T_c and OC operate in parallel to ground at front S_h , the leads from the control circuit to the group selector are closed, and sequence switch R leaves position 1, its circuit being closed over cam B and front OC. The relay OC remains locked-up over back L_m , and cam D to ground which is connected also over a resistance, cam E, front T_c , and brush j for operating relay CO of the selector.

Relay S_a is bridged across brushes a and b . On account of the low resistance of S_a the register E is started which in Fig. 2 is indicated by showing the impulse sender I connected to wire b and the starting relay D_i of the sender connected to wire a .

The relay S_a operates, energizes L_b and receives the selective impulses. The relay L_b remains actuated during the receipt of the impulses, and relay OC becomes de-energized. At the end of the series of impulses, one or two pairs of counting relays (EC, FC) are locked-up depending whether the digit received was lower or higher than 6. When the slow relay L_b releases at the end of the series of impulses, R moves out of position 4, and a high resistance relay H_r is connected in series with the impulse relay S_a in order to stop the register. From positions 1-4, H_r is short-circuited over cam S.

Between sequence switch position 4 in which the impulses are received and position 7 in which the selector is set, the digit received is transferred to the marker relays M_1 , M_2 , M_4 or M_6 . For example, M_2 is operated when sequence switch R moves from position 5 to 6 over cam H, front FC-2, cams F and D to ground. When the switch leaves position 6, the locking circuit of relays EC and FC is opened and then closed again over cam F in position 7, whereas the relays EC₁ and FC₁ are locally fed over cam M in order to permit that the balance of the group of counting relays insure continuous hunting by the selector.

In position 7 the following circuits are closed: (1) relay S, cam R, brush e of selector SG to ground; (2) magnet of SG, brush p of finder CG, front T_c , back contact of test relay H_c , cams E and D to ground.

The operating circuit of the counting relays is closed from position 6, ground, cam D, back S, armature FC6. Since FC₁ is operated, then EC₂ becomes energized. In position 7 relay S is operated and EC₂ and FC₂ are locked-up in series over back FC₃, cams F and D to ground.

Assuming that the signal consists of two impulses, relay M_2 will be locked-up and the selector will hunt for an idle trunk in the second level. When the selector SG leaves its home position the relay S releases the relay EC₃ operates. When the brush e of the selector contacts with the last terminal of the first level, the relay S is again operated and the relays EC₃ and FC₃ are locked-up in series, the relays EC₂ and FC₂ become de-energized. The relays J_a and J_b are now energized by a circuit over a back contact of J₂, front S, cam G, front EC₃, cam M, back PC₁, front M₂, back M₆, back M₁, and cams F and D to ground. J_a places ground on H_c but even if the latter responds to the potential on the terminals of the last trunk in the first level the selector cannot stop because its circuit is closed over the back contact of J₂, the front contact of S.

When the selector leaves the first level, S releases and H_c may then respond to the potential of a free trunk (ground at front contact of J_a,

winding of H_c , front T_c brush t of CG, front C₀, and brush d of selector SG). The relay S_c is operated when H_c becomes energized and connects over its front contact a direct ground to the brush j of the finder CG. The relay T of the selector is actuated and locks up to the wire c of the preceding selector and by opening the a and b wires leading to the control circuit causes the de-energization of relays S_a and H_r. The relays L_b and T_c become de-energized whereupon the sequence switch R is moved out of position 7 by a circuit closed over the back contact of L_b and cam B. The control circuit is now ready to receive a new call.

If the only free trunk in the selected level is the last one of the group, then the operation is somewhat different. When the selector leaves the last terminal of the first level the relay S releases and J₂ is locked-up in series with J_a and J_b. The relay EC₄ is operated over a circuit including the front contact of FC₃, the back contacts of FC₄, 5 and 6, the back contact of S and cam O to the ground. When brush e of the selector reaches the last terminal in the second level the relay S becomes energized and the relays J_a and J_b become de-energized. However, J₂ remains locked-up over a circuit including its right-hand winding, front contact of S and front contact of J₂ to ground. If this last trunk is free then the relay H_c operates and the control circuit is released as above described. On the other hand, if this last trunk is busy then the selector continues its rotation, S releases whereupon J₂ releases. After each level is traversed one pair of counting relays is energized which through the agency of relays PC₁ and PC₂ insures that the hunt continue. At the beginning of the rotation, the levels 1, 2, 3, 4 and 5 are marked over the back contacts of relays PC₁. When the selector reaches the last terminals of the fourth level, the relay FC₅ locks up in series with the relay EC₅ and the relay PC₁ operates and prepares a marking of the 6th, 7th and 8th levels.

The relay PC₂ is operated when the selector reaches the 8th level, the circuit extending over the winding PC₂, front PC₁, cam J, front FC₃. This relay prepares the marking of the levels 9 and 0. When the 9th level is reached the relay PC₁ is released and the relay PC₂ releases when the selector again returns to the first level.

Fig. 3c shows a modification of Fig. 3a. By means of this modified arrangement a trunk is engaged after the potential on the c wire and the presence of a ground on the a wire of the selector have been verified. In this case the operation of relay H_c causes the operation of an additional relay A_x which connects the a wire of the selector to a point connected over a high resistance to battery and also over the winding of an additional relay T_a having the same high resistance to ground. If ground is present on the a wire of the trunk then the relay T_a does not operate but a slow relay S_a becomes energized and connects direct ground over its front contact to the relay T of the selector which as previously described extends the chain towards the final selector and causes the release of the control circuit. If the trunk is busy then the relay T_a operates and disconnects relay H_c which by releasing restarts the rotation of selector SG.

Figs. 4, 4a and 4b illustrate the final selector and its control circuit. For the sake of simplicity the group counting relays in the control circuit never receives more than five impulses from the final selector under control during the

the circuit extending from battery to the c wiper of the final selector winding of C_t , front B, brush t of CF , front T_a , front T_a to ground. The relay T_a was energized by a circuit including cam I and the front contact S in position 9 of the sequence switch.

If the called line is busy then the relay C_t does not become energized and the slow acting relay L (Fig. 4a) energized by a ground applied thereto over the right-hand armature of T_a closes over its front contact and the cam N a circuit for moving the sequence switch out of position 9 whereupon the control circuit is released.

If the units impulses corresponds to the number of the first line of a P. B. X group then a relay T (Fig. 4a) is energized in series with the relay C_t of the final selector. If the line is free then the relay T operates and locks up over its second winding and short-circuits its first winding. When this happens the relay C_t of the final selector becomes energized. If, on the other hand, the line is busy then the relay T does not become energized and when relay L energizes the hunting for a P. B. X line is started.

In this case the relay P_b is actuated over a back contact of T , front T_{a1} , brush r of CF and brush R of SF . If the units digit is even then the relay M_1 which was de-energized will now be energized over the front contact of L, front P_b and back M_a . The relay M operates and reverses the connection of the relay S whereupon the latter becomes de-energized and causes the de-energization of T_a and thus of L. The power magnet of SF is again energized and the hunt continues. When the next terminals are engaged the relay S is energized by battery connected to the arc d . The relay T_a is again operated and if the line is busy the relay L operates. Over its front contact it maintains energized relay M_a which was locked-up in series with M_1 when relay L released. By opening its back contact the relay L causes the deenergization of relay M_1 . Relay S is now again connected to battery. T_a and L release and the final selector SF takes another step. If all the P. B. X lines are busy then the relay P_b releases as the wipers leave the next to the last terminal of the P. B. X group and the control circuit is released when relay R closes its front contact.

It will be noted that in Figs. 4a and 4b I have indicated in dotted lines those parts of the invention which have to do with the P. B. X hunting feature, the inclusion of which in the system is, of course, optional. Obviously, many other modifications will suggest themselves to those skilled in the art.

What is claimed is:

1. In an automatic telephone system, a plurality of numerically designated lines, means including a selector switch for connecting a calling line with a called line, said selector having sets of terminals arranged in numerical groups and a set of brushes cooperating with said terminals, a magnet for moving said brushes over said terminals, means for rendering busy said terminals, a control circuit, a control switch associated with said circuit, means for variably operating said control switch in accordance with various digits of the number of the called line, means for temporarily connecting said circuit with said selector, means for sending an impulse to said control switch from the selector for the engagement of each group of terminals by the brushes, means for operating said control switch by the last-mentioned impulses, and test means

in the control circuit responsive to the busy condition of said terminals for controlling the circuit of said magnet.

2. An automatic telephone system according to claim 1 and in which said control switch comprises a set of counting relays, an operating circuit for said relays, and two relays controlling said operating circuit, one responsive to impulses representing the called number and the other to impulses sent from the selector.

3. In an automatic telephone system, a plurality of numerically designated lines, means including two groups of selector switches for connecting a calling line with a called line, each selector having sets of terminals arranged in numerical groups, a set of brushes cooperating with said terminals and a magnet for moving said brushes over said terminals, a control circuit for each group of selectors, a control switch associated with each circuit, means for operating one control switch in accordance with one digit and the other control switch in accordance with another digit of the number of the called line, means for temporarily connecting one of said circuits with a selector of the first group taken into use, means for connecting the other of said circuits with a selector of the second group taken into use, means in each selector for sending an impulse to the associated control switch for the engagement of each group of terminals, circuits for the selector magnets controlled by means in the associated control circuit, and means for releasing a control circuit upon the completion of the operation of the associated selector.

35 4. The telephone system in accordance with claim 3, and in which each control switch comprises a set of counting relays responsive to the impulses representing the called line and to the impulses sent from the associated selector.

40 5. The telephone system according to claim 3, and in which the other control switch is operated in accordance with two digits of the called number and means for operating said other control switch in accordance with an impulse sent from the associated selector for each terminal engaged in a selected group.

6. In an automatic telephone system, a plurality of numerically designated lines, means including two groups of selector switches for connecting a calling line with a called line, each selector having sets of terminals arranged in numerical groups, means for rendering busy said terminals, a set of brushes cooperating with said terminals and a magnet for moving said brushes over said terminals, a control circuit for each group of selectors, a control switch associated with each circuit, means for operating one control switch in accordance with one and the other in accordance with two digits of the number of the called line, means for temporarily connecting said one circuit with a selector of one group taken into use, means for connecting the other circuit with a selector of the other group taken into use, means in the selectors of said one group for sending an impulse to the associated control switch for the engagement of each group of terminals,

60 means in the selectors of the second group for sending first an impulse to the associated control switch for the engagement of each group of terminals and then an impulse for the engagement of each set of terminals in a selected group, circuits for the selector magnets controlled by means in the associated control circuit, test means in each control circuit responsive to the busy condition of the terminals in the associated selector

65 70 75

5

selection of the tens as well as during the selection of the units. The relay S is bridged across the *e* and *d* brushes of the selector. This relay operates every time the brush *d* engages a terminal connected to the positive pole of the battery if the tens digit is even or to the negative pole of the battery if the tens digit is odd.

Only the brush *e* is used for selecting the units. The relay S is then connected to ground if the units digit is odd and to the positive battery if the units digit is even. The hunting for an idle PBX line is controlled by a current reversing relay. A preceding group selector stops at the terminals of a free final selector which applies a potential over the make-busy jack OJ and the back contact of relay C₀. Then, as in the case of a group selector, a potential is placed on the *b* wire by the register circuit. The relay S_t (Fig. 4a) becomes energized and causes, in turn, the energization of relays B and C_s (Fig. 4a).

The finders CF of all the idle control circuits will start hunting for the final selector taken into use, the circuit extending from battery, winding of magnet CF, back T_c, front C_s, jack OJ, cam C and back G_t to ground. When the selector is found the relays G_t and S_h become energized. Then the relays T_c and T_{c1} become energized in parallel, ground being applied at the front contact S_h. These relays connect through the conductors of the control circuit.

The relays R and B of the final selector are operated in parallel, ground being applied over brush *j* of CF, front T_c and cams K and J to ground. The sequence switch R is moved out of position 1 into position 4 by a circuit extending over cam B and front T_{c1} to ground.

The relay S_a is bridged across the wires *a* and *b*, starts the register and receives the numerical impulses therefrom. In response to the first impulse it causes energization of relay L_m over cam E which remains actuated during the sending of the impulses. Relay O_c which was energized over cam C when the sequence switch passed through position 2 becomes de-energized upon the energization of L_m and prepares the circuit for moving the sequence switch out of position 4. At the end of the tens series of impulses a pair of counting relays I_c and I_d is locked-up if the digit is lower than six and two pairs are locked-up if the digit is higher than six.

When at the end of the series of impulses the relay L_m releases, the sequence switch R leaves its position 4, ground being applied thereto over cam J. From position 4 to position 5 the marking relays M₁, M₂, M₄ and M₆ are supplied with current and locked-up in accordance with the following table:

Digit Received	Relay Actuated
1.	M.
2.	M ₂ .
3.	M ₁ , M ₂ .
4.	M ₄ .
5.	M ₄ , M ₁ .
6.	M ₆ .
7.	M ₆ , M ₁ .
8.	M ₆ , M ₂ .
9.	M ₆ , M ₂ , M ₁ .
0.	M ₆ , M ₄ .

Beginning with position 4½, the locking circuit of the relays I_c and I_d is opened and then reclosed in position 5½ by cam J. The units are then received on the counting relays in the same

6

manner as the tens. In position 5½ the circuit of the final selector magnet SF is closed over brush *p* of CF, front T_{c1}, back L, cam G, back E_{c0}, cam N to ground. The relay S is actuated every time the brush *d* engages a terminal connected to the negative battery if the digit is even (relay M₁ de-energized), or to the positive battery if the digit received is odd (relay M₁ energized). If, for instance, the digit 4 was registered by the marking relay, then the relay N₄ is locked-up and the relay E_{c4} is operated over the following circuit: Battery, winding of E_{c4}, back F_{d4}, front M₄, back M₆, cam I, back S to ground.

When the brush *d* of the final selector engages a terminal connected to the negative pole of the battery, the relay S is actuated and the pair of counting relays E_{c2} and F_{d2} is locked-up. When the wiper of the selector engages the next terminals which are connected to the negative pole of the battery, the relay S is again actuated and then falls off and the relays E_{c0} and F_{d0} are locked-up. At this moment the driving circuit of selector SF is transferred to the ground at the back contact of S over the left-hand contact of E_{c0}. When the brush *d* of the selector contacts with the next terminal (the 4th terminal connected to the negative pole of the battery) the relay S becomes energized and stops the selector SF, the wipers of which engage the terminals corresponding to the digit 4.

The units impulses are received on the relays I_c and I_d. In response to the first impulse the relay L_m becomes energized and remains locked-up during the sending of the impulses. Upon the termination of the units impulse the relay L_m falls off and the sequence switch R moves out of position 5½. The high resistance relay H is then energized in series with relay S_a over the *a* and *b* wires in order to maintain the control circuit and to prevent the energization of the supervisory relay of the connection circuit.

When the brush of the selector reaches the terminals designated by the impulses the relays E_{c0} and F_{d0} are locked-up and the sequence switch is moved out of position 6½ by a circuit including its cam B, front F_{d0}, front S to ground. The relays E_c and F_d are released because their locking circuit is opened in cam N.

When the sequence switch R reaches position 8 it will cause the setting of the selector SF in accordance with the units impulses. The circuit of the driving magnet is the same as during the tenths selector but the marking relays, after position 6½, (in which they were locked-up over cams L and M) are again fed over cams O, P, Q and R depending on the units digit received. If the units digit is 1 the relay M₁ is energized and connects relay S to ground. When the brush *e* of the final selector contacts with a terminal connected to battery, the relay S will become energized and stops the final selector because the pair of counting relays E_{c0} and F_{d0} are locked-up.

Beginning in position 7½, the ground at the back contact of relay S is connected over cam I towards the group of relay E_c—F_d, the circuit in the present case extending over back M₆, back M₄, back M₂, front M₁, back F_{d0}, winding E_{c0} to battery.

When the final selector contacts with the terminals represented by the units digit, the sequence switch R is moved out of position 8 by a circuit over cam B, front F_{d0} to ground at the front contact of S.

If the selected line is free then relay C_t of the final selector becomes energized and locked-up,

also controlling the associated magnet circuit, means for releasing said one control circuit upon the engagement by the associated selector of a set of idle terminals in the desired group, and means for releasing the other control circuit upon the engagement of the desired set of terminals in the desired group.

7. The telephone system according to claim 6, and in which means are provided in the second group of selectors for hunting for an idle set of terminals in a selected group, and means in the associated control circuit responsive to the busy condition of terminals for controlling the last-mentioned means.

8. The telephone system according to claim 6, and in which the one control switch comprises one set of counting relays and the other two sets of counting relays.

9. A telephone system according to claim 1, and in which said control switch comprises a plurality of pairs of counting relays forming a chain, circuits for energizing and locking up one pair of said relays if a digit of the called number has less than a given value and two sets if it has a given value or higher, a marking relay for each pair of counting relays and operated in response to the operation thereof, a circuit for operating a set of counting relays upon the engagement of each group of terminals by the selector brushes, means controlled by said marking relays to close the magnet circuit for operating said selector to hunt for a set of idle terminals in the selected group, two relays also controlling said magnet circuit to operate the selector to continue hunting for an idle set of terminals if all the terminals in the selected group are busy, an energizing circuit for one of said two relays closed upon the energization of the last pair in the counting relay chain, and an energizing circuit for the other of said two relays jointly controlled by the first one of the two and an intermediate pair of counting relays.

10. A telephone system according to claim 1, and in which said control switch comprises two sets of counting relays, a first impulse relay in said control circuit responsive to impulses representing two digits of the numerical designation of the called line, a circuit for operating the first set of counting relays controlled by said impulse relay in response to the first digit, means for releasing the counting relays of the first set and operating them under the control of the impulse relay in accordance with the second digit, a circuit for the selector magnet closed under the control of said counting relays, revertive impulses sent by the selector to said control circuit depending on the extent of movement of its brushes during the movement of the brushes from one group of terminals to another and also during the movement from one set of terminals to another in a selected group, a second impulse relay in the control circuit responsive to said revertive impulses, a circuit for operating the second set of counting relays controlled by the second impulse relay in accordance with the revertive impulses representing both operations of the selector, and means under the control of the second set of counting relays for opening the circuit of the selector magnet.

11. A telephone system according to claim 1, and in which said control switch comprises two sets of counting relays, a first impulse relay in said control circuit responsive to impulses representing two digits of the numerical designation of the called line, a circuit for operating the first

set of counting relays controlled by said impulse relay in response to the first digit, means for releasing the counting relays of the first set and operating them under the control of the impulse relay in accordance with the second digit, a plurality of marking relays, circuits for operating one of said marking relays depending on the operations of said first set of counting relays, a circuit for the selector magnet closed by said marking relays, revertive impulses sent by the selector to said control circuit depending on the extent of movement of its brushes during the movement of the brushes from one group of terminals to another and also during the movement from one set of terminals to the other in the selected group, a second impulse relay in the control circuit responsive to said revertive impulses, a circuit for operating the second set of counting relays controlled by the second impulse relay in accordance with the revertive impulses representing both operations of said selector, and means under the joint control of said marking relays and the second set of counting relays for opening the circuit of the selector magnet.

12. In an automatic telephone system, a plurality of numerically designated lines, means including a group of selector switches for establishing a conversation circuit between a calling and a called line, each selector having a plurality of sets of terminals arranged in groups, each set of terminals comprising two in the conversation circuit and a test terminal, said selector having three brushes cooperating with said terminals, a magnet in each selector for moving said brushes over said terminals, a control circuit, a control switch associated with said circuit, means for temporarily connecting said circuit with a selector taken into use, means for operating said control switch in accordance with the number of the called line, means in each selector for sending an impulse to said control switch for the engagement of each group of terminals, a first relay in said control circuit having a winding connected with the brush of the selector cooperating with the test terminal, means for applying a distinctive potential to the test terminal and to one of the terminals in the conversation circuit, a second relay in the control circuit operated upon the energization of the first relay, a third relay in the control circuit operative thereupon and responsive to the distinctive potential on the conversation terminal engaged by the selector brushes, said third relay having a contact in the circuit of the first relay, and means for releasing the control circuit and seizing a set of terminals also controlled by the third relay.

13. In an automatic telephone system, a plurality of numerically designated lines, means including a group of selector switches for establishing a conversation circuit between a calling and a called line, each selector having a plurality of sets of terminals arranged in groups, each set of terminals comprising two in the conversation circuit and two other terminals, said selector having four brushes cooperating with said terminals, a magnet in each selector for moving said brushes over said terminals, a control circuit, a control switch associated with said circuit, means for operating said control switch in accordance with the number of the called line, means for temporarily connecting said circuit with a selector taken into use, means including a brush cooperating with one of two other terminals for sending an impulse to said control switch for the engagement of each group of terminals, a first relay

in said control circuit having a winding connected with the brush of the selector cooperating with the second of the two other terminals, means for applying a distinctive potential to the last-mentioned terminal and to one of the terminals in the conversation circuit, a second relay in the control circuit operated upon the energization of the first relay, a third relay in the control circuit operative thereupon and responsive to the distinctive potential on the conversation terminal engaged by the selector brushes, said third relay having a contact in the circuit of the first relay, and means for releasing the control circuit and seizing a set of terminals also controlled by the third relay.

14. In an automatic telephone system, a plurality of numerically designated lines, means including one of a group of selector switches for establishing a conversation circuit between a calling and a called line, each selector having sets of terminals, each set comprising two terminals in the conversation circuit and three other terminals, a set of five brushes for each selector cooperating with said terminals, a magnet in each selector for operating the brushes successively to engage said sets of terminals, a control circuit, means for associating the control circuit with a selector taken into use, a first set of counting relays in said circuit, a first impulse relay for controlling the operation of said counting relays, a circuit for said impulse relay including two brushes of said selector cooperating with two of the three other terminals, distinctive potentials applied to alternate terminals with which one of said two brushes cooperates, distinctive potentials applied to alternate terminals with which the other of said two brushes cooperates, test potentials applied to the third of said other terminals, a test relay in said control circuit responsive to the test potentials, a second impulse relay for controlling said set of counting relays, means for operating said second impulse relay in accordance with the numerical designation of the called line, a second set of counting relays controlled by the first impulse relay, and a circuit for the selector magnet controlled by said test relay.

15. In an automatic telephone system, a plurality of numerically designated lines, means including one of a group of selector switches for establishing a conversation circuit between a calling and a called line, each selector having sets of terminals, each set comprising two terminals in the conversation circuit and four other terminals, a set of six brushes for each selector cooperating with said terminals, a magnet in each selector for operating the brushes successively to engage said sets of terminals, a control circuit, means for associating the control circuit with a selector taken into use, a first set of counting relays in said circuit, a first impulse relay for controlling the operation of said counting relays, a circuit for said impulse relay including a rectifier and two brushes of said selector cooperating with two of the four other terminals, ground potential applied to alternate terminals and negative potential applied to the other terminals with which one of said two brushes cooperates, negative potential applied to alternate terminals and positive potential to the other terminals with which the other of said two brushes cooperates, test potentials applied to the third of said four other terminals, a first test relay in said control circuits responsive to said test potential and controlling the direction in which the current flows through the impulse relay, test potentials applied to the fourth of said four other

terminals, a second test relay in said control circuit responsive to the last-mentioned test potential, a second impulse relay for controlling said set of counting relays, means for operating said second impulse relay in accordance with the numerical designation of the called line, a second set of counting relays controlled by the first impulse relay, and a circuit for the selector magnet controlled by said test relays and two sets of counting relays.

16. An automatic telephone system according to claim 14, and in which the second impulse relay is responsive to impulses representing two digits of the numerical designation of the called line, a circuit for operating the first set of counting relays controlled by said second impulse relay in response to the first digit, means for releasing the counting relays of the first set and operating them under the control of the second impulse relay in accordance with the second digit, a plurality of marking relays, circuits for operating one of said marking relays depending on the operations of said first set of counting relays, the circuit of the selector magnet being under the joint control of said marking relays and the second set of counting relays.

17. An automatic telephone system according to claim 1, and in which said test means comprises a normally inoperative relay, and means for rendering said relay operative only when there is agreement between the operation of the control switch in accordance with the called number and the functioning of the selector.

18. In an automatic telephone system, a plurality of numerically designated lines, means including a group of selector switches for establishing a connection between a calling and a called line, each selector having a plurality of sets of terminals arranged in groups and a set of brushes cooperating with said terminals, a magnet in each selector for moving said brushes over said terminals, a control circuit, a control switch associated with said circuit, means for temporarily connecting said circuit with a selector taken into use, means for operating said control switch in accordance with the number of the called line, a circuit for the selector magnet closed upon the operation of the control switch, means in each selector for sending an impulse to said control switch for the engagement of each group of terminals by the selector brushes, means for applying a distinctive potential to one of the terminals of each set to indicate its busy condition, a relay in the control circuit responsive to the distinctive potential on the terminals closing the circuit of the selector magnet while the selector brushes engage busy terminals in the selected group, and means for operating the control switch in accordance with the impulses sent by the selector after engaging all the terminals in a group and finding them busy.

19. In an automatic telephone exchange system, a plurality of numerically designated lines, means including a group of selector switches for connecting a calling line with a called line, each selector having sets of terminals arranged in groups and a set of brushes cooperating with said terminals, a magnet in each selector for moving said brushes over said terminals, a control circuit, a control switch associated with said circuit, means for temporarily connecting said circuit with a selector taken into use, means for operating said control switch in accordance with the number of the called line, a set of counting relays in said control circuit, a circuit for marking a

counting relay in accordance with said operation of the control switch, means in each selector for sending an impulse to said counting relays for the engagement of each group of terminals, and a circuit for the selector magnet jointly controlled by said control switch and the marked counting relay.
